UNITED STATES PATENT OFFICE.

HENRY BOARDMAN, OF DES MOINES, IOWA.

SPRING-WHEEL.

1,075,688.

Specification of Letters Patent.

Patented Oct. 14, 1913.

Application filed March 29, 1913. Serial No. 757,680.

To all whom it may concern:

Be it known that I, HENRY BOARDMAN, a citizen of Great Britain, residing at Des Moines, in the county of Polk and State of Iowa, have invented certain new and useful Improvements in Spring-Wheels, of which the following is a specification, reference being had to the accompanying drawings.

This invention comprehends certain new and useful improvements in resilient wheels and has for its primary object to provide a resilient wheel composed of a number of tread sections each provided with separate supporting springs and shock absorbing and equalizing springs, each tread section being engaged over and inclosing the springs of the section immediately ahead, thereby forming resilient connections between the tread sections.

Another object is to provide a resilient wheel which will be of extremely simple construction, cheap to manufacture and highly efficient and effective in use.

A further object is to generally improve and simplify the construction of devices of this character and increase the efficiency and durability of the same.

With the above and other objects in view, this invention consists in the novel features of construction, combination and arrangements of parts to be hereinafter more fully described, claimed and illustrated in the accompanying drawings, in which—

Figure 1, is a fragmentary elevational view partly in section of the preferred form of my improved resilient wheel. Fig. 2, is a similar view of a similar modified form of my invention. Fig. 3, is a fragmentary detail view of the same, showing the manner in which the main springs are connected. Fig. 4, is a fragmentary longitudinal section of a third form of my invention. Fig. 5, is a detail plan view of one of the main springs removed. Fig. 6, is a view similar to Fig. 4, showing a fourth or further modified form. Fig. 7, is a like view showing a fifth or still further modified form. Fig. 8, is a detail perspective view of one of the main springs employed in the last form, or form shown in Fig. 7. Fig. 9 is a detail sectional view.

Referring more specifically to the drawings in which similar reference characters designate corresponding parts throughout the several views, 1 designates the wheel rim over which are engaged a plurality of

semi-cylindrical members 2 having the pliable tread sections 3 preferably of rubber or leather secured upon their central portion, which sections have their opposite longitudinal edges engaging the sides of the members 2 outwardly of the longitudinal edges thereof. The members 2 are connected by the links 2' upon their outer faces, which links have their opposite ends pivoted to the adjacent members as shown at 2''.

Depending from each longitudinal edge of each member 2 is a perforated ear 4 which depends below the wheel rim 1. The opposite perforated ears 4 of each member 2 are connected by a connecting pin 5 extending transversely beneath the rim 1, thereby limiting outward movement of the members 2.

Each member 2 has a pair of bearing and closure strips 6 secured to its inner edge at one end and adapted for engagement with the adjacent end of the member immediately ahead, the rear end of the last mentioned member resting upon said strips.

Each member 2 is resiliently supported in its outermost position by means of a spring 7 which has its upper edge extending longitudinally within the member 2 and secured to the central portion thereof, said spring projecting for a short distance rearwardly of the member 2 and then being directed downwardly at an angle, as shown at 8. Then the spring is given a turn or coil, as shown at 9 and extended forwardly toward the member to which the upper end 90 of the spring is secured, as shown at 10. This last mentioned end of the spring is secured upon the upper face of the rim 1, in any suitable manner.

Loosely mounted upon the inclined portion 8 of each spring 7 is a bracket member 11 which is movable longitudinally of the inclined portion of said spring and has secured therein one end of a spring carrying rod 12 which is engaged through the rim 1 and has the upper and lower springs 13 and 14 respectively mounted thereon above and below the rim. A bearing collar 15 is mounted upon the rod 12 and one end of the upper spring 13 is engaged with this collar while the opposite end of said spring is engaged against the outer face of the wheel rim 1. A collar 16 is mounted upon the free end of the rod 12 and one end of the lower spring 14 is rigidly secured to this collar while the opposite end of said spring is secured to a screw or the like 17 engaged

in the lower or inner face of the rim 1. It will be understood that the wheel rim 1 is connected with the hub 18 by means of the spokes 19 in any preferred and well known manner, the principal part of my invention, however, being the construction and arrangement of the semi-cylindrical members 2 and the manner in which said members are resiliently mounted upon the rim 1 and connected with one another.

In the second form of my invention shown in Figs. 2 and 3, I have shown each spring 7 as having its free end extended downwardly and perforated, as shown at 20 to receive a pivot pin 21 engaged therethrough and through the opening 22 formed in the slanting portion 8 of the spring 7 immediately ahead, thereby forming a pivotal connection between the springs ahead. By connecting the springs 7 in this manner, the strain is more equally distributed and independent longitudinal movement of the spring 7 is prevented. The remaining parts of the wheel, are substantially the same as in the first or preferred form.

In the third form shown in Figs. 4 and 5, I have employed a wire spring 23 which is bent in substantially U-shaped form and given a turn, as shown at 24 to form the loop 25 at its central portion, which is bent downwardly, the purpose of which will presently appear. The opposite legs of the spring 23 are also looped along their inclined portions, as shown at 26, the loops 26 being directly opposite one another and having a pivot pin 27 positioned therethrough, which pivot pin is also engaged through the loop 25 of the next spring 23, thereby properly connecting the springs. The legs of each spring 23 are also looped or coiled, as shown at 28 adjacent their free ends to correspond with the coiled portions 9 of the springs employed in the first and second forms of my device, and the ends of the legs are then secured to the rim 1, as shown at 29. The bracket member 11 is engaged over the inclined portions of the opposite legs of the springs 23 and secured in adjusted position longitudinally upon said legs by the set screws 11', as will be clearly understood by referring to the drawings. The coil expansion and shock absorbing springs 13 and 14 are employed and arranged in this form the same as in the previously described forms. This form is especially adapted for wheels to be employed upon light vehicles.

In the fourth form shown in Fig. 6, I have employed a heavy leaf spring 30 having its horizontal portion secured to the semi-cylindrical member 2 in the same manner as in the previous forms and having the downwardly directed ears 31 at its upper free end for receiving the pivot pin 32 passed through the inclined portion of the spring 30 immediately ahead, as described in

the previous forms. The inclined portion of the springs 30 are indicated by the numeral 33 and said springs are bent upon themselves at the lower ends of their inclined portions, as shown at 34 and extended forwardly and secured to the outer face of the rim 1, as shown at 35. In this form I employ extra supporting springs 36 which are secured at their lower ends upon the lower forwardly directed ends of the springs 30 by the fastening means 35 employed for securing these ends to the rim 1. The upper ends of the springs 36 are engaged against the upper ends of the springs 30 and secured to the same and to the semi-cylindrical members 2, as shown at 37, the inclined portions of the springs 36 being spaced inwardly of the inclined portions of the springs 30. The springs 36 are double at their lower portions, as shown at 38, the extra short spring having its upper end clamped to the long spring by means of the clamping bracket 39 which is secured in position by the clamping or set screws 40. In this case, the bracket member 11 is secured to the inclined portion of the long extra spring 36 above the upper end of the short extra spring and the springs 13 and 14 are mounted upon the pin 12 having one end secured in the bracket 11, as previously described.

In the fifth form shown in Figs. 7 and 8, I have employed the spring 33 constructed in the manner described in the fourth form but composed of heavy material and therefore considerably thicker than in the fourth form. In this last instance, I have dispensed with the use of the extra springs 36 and have secured the bracket member 11 to the inclined portion 33 of the spring 30. I have connected the springs 30, however, in the same manner as previously described and the arrangement of the springs 13 and 14 upon the rod 12 is the same as in the previous forms.

While I have shown the preferred forms of my device, it will be understood that other changes may be made in the construction and arrangement of the various parts of my invention within the scope of the appended claims without departing from the spirit of my invention.

Having thus described my invention, what I claim is:—

1. A resilient wheel including an inner rim, a sectional outer rim, a spring for each section and having an inclined portion between the inner and outer rims while the inner end of the spring is bent back upon itself and secured to the inner rim and the outer end of the spring is bent at an angle to the inclined portion thereof and secured to the outer rim section, the bent back portion of the spring being inwardly of the adjacent section of the outer rim, a rod adjust-

ably secured to the inclined portion of each spring and extended through the inner rim, and equalizing springs mounted upon each rod and bearing against the inner and outer 5 faces of the inner rim.

2. A resilient wheel including an inner rim, a sectional outer rim, a spring for each section and having an inclined portion between the inner and outer rims, the inner 10 end of the spring being bent and secured to the inner rim while the outer end of the spring is bent at an angle to the inclined portion thereof and secured to the outer rim section, a second spring for each section having an inclined portion inwardly of the inclined portion of the first spring, the inner 15 end of the second spring being bent at an

angle and secured upon the inner end of the first spring while the outer end of the second spring is secured against the outer end 20 of the first spring, connections between the springs of each section, a rod loosely connected to the inclined portion of each second spring and extended through the inner rim, and equalizing springs mounted upon each 25 rod and bearing against the inner and outer faces of the inner rim.

In testimony whereof I hereunto affix my signature in the presence of two witnesses.

HENRY BOARDMAN.
